US0D1094171S

(12) **United States Design Patent** (10) **Patent No.:** **US D1,094,171 S**
Thélonious (45) **Date of Patent:** **** Sep. 23, 2025**

(54) **PLANTER**

- (71) Applicant: **Vitra AG**, Birsfelden (CH)
- (72) Inventor: **Goupil Thélonious**, Saint-Pierre-en Port (FR)
- (73) Assignee: **Vitra AG**, Birsfelden (CH)
- (**) Term: **15 Years**
- (21) Appl. No.: **29/893,008**
- (22) Filed: **May 24, 2023**

Related U.S. Application Data

- (63) Continuation of application No. 29/889,347, filed on Apr. 11, 2023, now Pat. No. Des. 1,069,641.
